RAIL ANCHOR

Application filed September 18, 1929. Serial No. 393,487.

Our invention relates to improvements in rail anchors, particularly to a type of anchor adapted to be sprung over the base portion of a railroad rail in a position to bear against the vertical face of a cross tie.

One of the objects of the invention is to provide an anchor device of the above character which may be conveniently formed from a metal bar of suitable thickness to permit the anchor to be readily flexed onto the rail, but which when applied in its operative position, will exert a strong grip on the rail and also present a tie abutment of relatively large bearing area adapted to bear against a vertical face of an adjacent cross tie. In this connection, the invention contemplates as one of its specific objects the provision of a tie abutting portion of suitable bearing area without changing the cross-sectional shape 20 of the bar from which the anchor is made and without extending the tie abutting portion to an objectionable distance below the bottom surface of the rail, thereby providing an abutment having sufficient area to avoid 25 injuring the cross tie and at the same time provide sufficient rigidity to avoid objectionable distortion of the tie abutting portion when it is pressed against the cross tie.

Another object is to provide, in a rail anchor device adapted to be applied to a rail by engaging one end of the anchor over one flange of the rail base and then pulling the other end upwardly across the edge of the other base-flange, a one-piece construction in 35 which the distortion of the under rail portion of the device, during its application to a rail, will not interfere with the production of a firm grip on the bottom surface of the rail base adjacent opposite edges thereof.

A further object is to provide an improved anchor device and method of applying the same, which does not require the use of a special applying implement. In this connection the invention includes a rail anchor construction in which one anchor may be readily used in combination with any available bar for exerting the upward pulling force above mentioned, the loop end of one 45 anchor serving as a link connection between

the end of the bar and the anchor being applied.

In the drawing:

Fig. 1 is a side view of a rail anchor constructed in accordance with our invention applied to the base portion of a railroad rail, illustrating in dotted lines the normal contour of the under-rail portion of the anchor before it is applied to the rail and also illustrating the use of an anchor as a part of the applying implement. 55

Fig. 2 is a side view similar to Fig. 1 but showing the anchor in a position which it assumes before the loop end thereof is flexed over the base flange of the rail, and before the 60 downwardly bowed under-rail portion is flexed upwardly by the forces exerted during the application of the anchor to the rail, and

Fig. 3 is a view of the anchor device corresponding to the position of the anchor in Fig. 1, Fig. 3 being taken from the side of the rail looking toward the loop end of the anchor. 70

The embodiment of our invention shown in the accompanying drawing comprises a body portion 10 which is normally bowed downwardly when free of the rail to compensate for the upward arching of said portion during the applying movement and thereby provide a bearing against the bottom surface of the base at opposite edges thereof. Preferably the bowed contour is such that, when the anchor is fully applied, the under-rail portion bears against the bottom of the rail 11, adjacent the opposite edges of the base but remains out of contact with the center portion of said base surface. One end of the body is turned inwardly toward the web of the rail to provide a jaw 12 for engagement over one flange 13 of the rail base 13 and to provide also an upstanding portion 14 which normally bears against the vertical edge of the rail base. The other end of the body is formed with an upstanding resilient loop 15, a portion of which normally projects over the upper surface of the other flange of the rail base. The end portion 16 of the loop extends downwardly to provide a portion for bearing against the vertical face of the cross tie 17 100

and is formed at its extremity with an angular, preferably upturned portion 18. The loop 15 is preferably formed by bending the end portion 16 upwardly and then downwardly across the body 10 at a point near the edge of the rail base, whereby the curved portion 19 of the loop projects over and bears against the upper corner portion of the flange 20 of the rail base. The hook portion 18 of the tie abutment, preferably projects under the rail and thereby extends its tie engaging face inwardly toward the center of the rail.

In applying the anchor to a rail, the jaw 12 is first hooked over one flange of the rail base in the position shown in Fig. 2. In this position of the anchor the curved portion 19 of the loop 15 bears against the lower corner of the base flange 20 of the rail. By forcing the loop end upwardly across the edge of said base flange, the loop portion is flexed until it clears the upper corner of said base flange. The stresses incident to applying the anchor tend to flex the portion 10 upwardly toward the bottom surface of the base, but, due to the bowed contour of the bar, it normally remains out of contact with the central portion of the rail base, thereby insuring in all installations a firm contact with the bottom of the base adjacent the opposite edges thereof. The reflex action of the loop exerts a strong spring grip transversely of the rail and also exerts a vertical grip for holding the body portion 15 of the anchor up against the bottom surface of the rail base.

In the drawing, we have illustrated a method of applying the rail anchor which permits the use of any available bar. In the drawing, a bar 21 is shown bearing upon the head 22 of the rail and connected, by use of an anchor device 23 as a link, to the loop 15 of the anchor being applied, whereby great force can be exerted to pull the loop end of the anchor upwardly across the edge of the base flange 20 of the rail. The large loop 15 of the anchor provides a suitable opening to receive the end of the bar 21 and the hook portion 18 may be readily engaged with the loop portion 15 of the anchor being applied to the rail.

While we have illustrated herein a rail anchor of certain specific construction, including the use of round metal stock, it will be understood that we do not wish to be limited to the specific features except insofar as the claims are expressly limited.

We claim:

1. A rail anchor comprising a bar formed at one end with means for engagement with one flange of a rail base and at the other end with a loop having a downturned end adapted, on upward movement of said loop end, to be sprung into resilient gripping engagement with the other flange of the rail base,

and an inwardly projecting hook portion at the extremity of said downturned portion for bearing against a cross tie and for engagement with a portion of another anchor during the application of the latter to a rail.

2. A rail anchor comprising a bar formed at one end with means for engagement with one flange of a rail and at the other end with a resilient loop, a portion of which loop extends downwardly across the body and is adapted to be flexed, on upward movement of the said loop end, into spring gripping engagement with said rail base, the said downwardly extending portion of said loop being formed at its lower end with a hook portion providing a tie abutment which projects under the base flange of the rail and the extremity of said hook portion being spaced from the under rail portion of the anchor to permit engagement with the resilient loop of another anchor to facilitate application of the latter to a rail.

3. A rail anchor for resiliently gripping opposite edges of a rail base and comprising a bar hooked at one end to provide a jaw for engagement with one flange of a rail base and looped upwardly and downwardly across the bar at the other end to provide a portion overlying the upper surface of the rail base and adapted to be flexed over said rail base on upward movement of the loop, and a hook portion at the extremity of the downturned portion of the loop for bearing against a cross tie and for engagement with the loop portion of another anchor to facilitate application of the latter to a rail.

4. A rail anchor formed at one end with means for engagement with one flange of a rail base, an upstanding loop at the other end for resiliently engaging the other base flange of the rail, a hook portion disposed at the extremity of said loop for engagement with the loop end of an anchor being applied in the manner specified.

5. A rail anchor comprising an under-rail portion formed at one end with means for engagement with one flange of a rail base and at the other end with a resilient loop adapted to flex outwardly relative to the rail, on upward movement of the anchor, into spring gripping engagement with the other flange of the rail base; said under-rail portion being normally bowed downwardly, when free of the rail, to compensate for the upward distortion of said under-rail portion during the outward flexing movement of said loop, whereby a firm bottom bearing is insured adjacent the opposite edges of the rail base.

6. A rail anchor comprising an under-rail portion formed at one end with means for engagement with one flange of a rail base and at the other end with resilient loop adapted to flex, on upward movement of the anchor, into spring gripping engagement with the

other flange of the rail base; said under-rail portion being normally bowed downwardly, when free of the rail, to compensate for the upward flexing thereof during the application of the device to a rail, the bow of the under-rail portion being so proportioned with relation to the normal distortion of the loop that the said upward flexing of the under-rail portion will not extend above the horizontal, thereby insuring a firm contact with the bottom surface of the rail base adjacent the opposite lower corners thereof.
